UNITED STATES PATENT OFFICE.

LEWIS DODGE AND CHARLIE B. DODGE, OF MORSE BLUFF, NEBRASKA.

PNEUMATIC FOOT.

1,352,943.

Specification of Letters Patent. Patented Sept. 14, 1920.

Application filed February 9, 1920. Serial No. 357,184.

To all whom it may concern:

Be it known that we, LEWIS DODGE and CHARLIE B. DODGE, citizens of the United States, residing at Morse Bluff, in the county of Saunders and State of Nebraska, have invented certain new and useful Improvements in Pneumatic Feet, of which the following is a specification.

This invention relates to improvements in artificial feet and means for so arranging said artificial feet inside the boot or shoe that when in use, it will simulate the action of the human foot, as shown and described in our application for Letters Patent for pneumatic feet, filed October 6th, 1919, Serial Number 328,832. The object of our invention is to provide a durable, a practical and an inexpensive artificial pneumatic foot, whose ease of operation and smoothness of action are such that the wearer will experience little or no jar or discomfort to the leg or body when he throws his weight upon the foot in the act of walking.

With these and other objects in view, which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood, there are shown, in the accompanying drawings, means for carrying the same into practical effect without limiting the improvements in their useful applications to the particular constructions, which, for the purpose of explanation, have been made the subject of illustration.

In said drawings—

Figure 1 is a vertical sectional view of our pneumatic foot;

Fig. 2 is a detail plan view of the bottom of the foot, a portion of the covering being removed so as to more clearly show the arrangement of the wires or springs embedded therein;

Fig. 3 is a detail plan view of the heel of our pneumatic foot showing the opening therein for the introduction of the inner tube; and

Fig. 4 is a horizontal sectional view taken along the line 4—4 of Fig. 1.

Similar reference characters designate

like parts or features in the several figures of the drawings.

Referring to Fig. 1, the letter A shows the lower portion of an artificial leg, and the letters B, C, D represent spring steel fasteners or supporters which are embedded in the fabric walls of the covering or casing 1, three on each side of the foot, at or about the ankle; the supporters B, D, and those oppositely located, being forked at their lower ends. Their position with respect to the foot and with respect to each other is more clearly shown in cross section in Fig. 4. As shown in Fig. 1 there is a hole in each supporter near its upper end so as to permit of insertion of a screw or bolt to secure the upper portion of our artificial foot to the lower end of the wooden leg which extends upwardly therefrom. At and above the point indicated by the line 4—4 in Fig. 1, the front portion of the outer covering is slotted, see letter E, Fig. 4, and we provide eyelets and laces F so that the covering can be tightly laced at this point about the lower portion of the artificial leg and thus assist in firmly maintaining the lower portion of the foot in its proper position. Our pneumatic foot consists of two parts, namely, the inner tube or bladder and the outer covering or casing 1, made of rubber fabric in which is embedded spring steel strips or bands, 4, as more clearly shown in Fig. 2, the purpose of which is to make the structure strong and durable and at the same time to assist in giving a spring-like motion to the foot when the same is in use in the act of walking.

Both leather and canvas have been found in practice to be unsuitable as an outer covering or casing, but rubber fabric, such as used in automobile tires, although of somewhat lighter texture, has proved very satisfactory.

Referring again to Fig. 1, it will be noted that the steel strips or bands 4, begin at a point slightly above the instep, continue down to and over the toe 6, curving backwardly into the sole 7 throughout its length to the rear of the foot where they curve upwardly into the heel 8, terminating at a point about an inch or so above the sole.

The rubber fabric in which the steel springs are embedded, while of strong and durable construction, is however, made with a due regard to the comfort of the wearer,

and in varying degrees of thickness, a casing for a man of heavy weight requiring a stronger and heavier construction than one for a man of medium or light weight.

5 At a point 5 in the outer casing 1, said inner tube is provided with a metal tube 10 having a valve located therein and a screw cap 11, the construction of which is similar to those in use upon the inner tubes of automobile tires so as to permit of the proper 10 inflation of said inner tube or bladder when necessary.

15 Referring now to Fig. 3, it will be observed that a portion of the casing is cut away or slotted in such manner as to permit of the insertion of the inner tube or bladder 3, and laces and eyelets 9 are provided along the edges of said opening so that the parts may be tightly laced after 20 the inner tube or bladder is in place.

What we claim is:

1. In an artificial foot, the combination 25 of an outer casing of rubber or rubber fabric substantially of the shape of the human foot, its upper part being provided with metallic braces or supports embedded in the fabric on each side of the leg at or about the location of the ankle and means to secure them to an artificial leg, with an opening in the 30 outer casing for the insertion of an inner tube, an inner tube of soft rubber substantially of the configuration of the outer casing, adapted to fit within the latter and means which will permit and control the 35 inflation of the inner tube.

2. In an artificial foot, the combination

of an outer casing of rubber or rubber fabric substantially of the shape of the human foot, its upper part being provided with metallic braces or supports embedded in the 40 fabric on each side of the leg at or about the location of the ankle and means to secure them to an artificial leg, with an opening in the heel of the outer casing for the insertion of an inner tube, an inner tube of soft rubber 45 substantially of the configuration of the outer casing, adapted to fit within the latter and means which will permit and control the inflation of the inner tube.

3. In an artificial foot, the combination 50 of an outer casing of rubber or rubber fabric substantially of the shape of the human foot, its upper part being provided with metallic braces or supports embedded in the fabric at substantially opposite points on 55 each side of the leg at or about the location of the ankle to secure it to an artificial leg, said upper part being further provided with a slotted opening therein and means for tightly drawing its marginal edges close 60 about the artificial leg and an opening in the heel of said casing for the insertion of an inner tube, with an inner tube of soft rubber substantially of the configuration of the lower part of the outer casing, adapted 65 to fit within the latter and means which will permit and control the inflation of the inner tube.

In testimony whereof we affix our signatures.

LEWIS DODGE
CHARLIE B. DODGE.
